CLAIM

The ornamental design for a golf club head sole, as shown and described.

DESCRIPTION

FIG. 1 is a back side perspective view of a golf club head sole;

FIG. 2 is a heel side view thereof;

FIG. 3 is a back view thereof;

FIG. 4 is a front view thereof;

FIG. 5 is a bottom view thereof; and,

FIG. 6 is a toe side view thereof.

The golf club head sole portions outside the phantom lines do not form any portion of the present invention.
